CONVERTIBLE BOOT DRIER AND TABLE

Genevieve M. Winckler, 824 Balfour Road,
Grosse Pointe Park, Mich.

Filed Mar. 10, 1961, Ser. No. 64,212

Term of patent 14 years

(Cl. D33—14)

FIG. 1.

FIG. 2.

FIG. 3.

FIGURE 1 is a perspective view of the convertible boot drier and table when it is in a position to serve as a boot drier.

FIGURE 3 is a side elevational view of the convertible boot drier and table when it is in an inverted position to serve as a table.

The top of the convertible boot drier and table, when serving as a table as illustrated in FIGURE 3, is conventionally plain.

I claim:

The ornamental design for a convertible boot drier and table, substantially as shown and described.
